(57) **CLAIM**

The ornamental design for a display screen with animated graphical user interface as shown and described.

DESCRIPTION

FIG. 1 is a front view of a display screen with animated graphical user interface showing the first image of the first embodiment of our new design;

FIG. 2 is the second image thereof;

FIG. 3 is the third image thereof; and,

FIG. 4 is the fourth image thereof.

The appearance of the animated graphical user interface sequentially transitions between the images shown in FIGS. 1 through 4. The process or period in which one image transitions to another image forms no part of the claimed design.

The broken line showing of the display screen and portions of the graphical user interface form no part of the claimed design.
